(57) **CLAIM**

The ornamental design for an atomizer of electronic cigarette, as shown and described.

DESCRIPTION

- 2. Atomizer of electronic cigarette
- 3. Atomizer of electronic cigarette
- 2.1: Perspective
- 2.2: Perspective
- 2.3: Front
- 2.4: Back
- 2.5: Left
- 2.6: Right
- 2.7: Top
- 2.8: Bottom
- 3.1: Perspective
- 3.2: Perspective
- 3.3: Front
- 3.4: Back
- 3.5: Left
- 3.6: Right
- 3.7: Top
- 3.8: Bottom

As seen from the drawings, the industrial designs of designs 2-3 to be claimed are characterized by the composition of the main composite elements: the main body is a U-shaped columnar structure; a left side of the top is arranged with a spout, which is an elliptical columnar structure with a taper; and a right side of the top is arranged with a rounded

(Continued)

transition shoulder; the difference between design 2 and design 3 is that the main body of design 3 is longer than that of design 2. The claimed product may be made in the conditions of modern production using modern technologies and materials.

1 Claim, 16 Drawing Sheets
